Isaac Dearborn

No. 38

The following improvement, has been patented and making part of the same containing a description of the means of the said Isaac Dearborn, formerly of the Improvement in the burning bunsen of the lamp, used in light houses.

In all light houses these bunsen burners —

Be it known that Isaac Dearborn of Bristol in the County of Bristol & State of Maine, Merchant of the United States Light House at Pemaquid in said State, have invented a new and useful improvement in making or constructing the bunsen burner of the lamp used in the Light House of the United States, and which shall be known in the improved burner of the lamp, and that the following is a full and exact description thereof, to the best of the knowledge of the inventor, and used in the United States Light Houses with the point ground on this lamp tube, one hundred and twenty one if donee base of the burner is mounted and on this tube a removable lamp handle thereon is an iron tube and one weight upon which which is fitted with a female is rendered within it becomes ignited by the burning of the lamp wick and a small one placed on the tube, by which improvement the burner may be rendered to be replaced as the lamp will now be ignited by the burning of the lamp wick, having previously by said handle and by means of a iron streak of iron for the top of the burner a better light is obtained. What follows is my invention and not previously known in the above description and this is the making and applying a removable

trap furnace, as before mentioned, to the top of the inc-
ense burner of the lamp. Which furnace when closed
by the burning spirit, is easily removed
and its place supplied by a new one, by which great
expense in repairing Light-House apparatus is saved
and all delay avoided, and a better light obtained.

The description by the accompanying drawing
is as follows. A. The burner. B. The furnace fitted on
the burner. C. Burner with furnace off. D. the three
trips taken at the end of the burner to the furnace.

In testimony whereof I the said Isaac Dimick
have hereunto set my hand this sixteenth day of
April in the year of our Lord Eighteen hundred
and thirty six.
